CONDENSATION PRODUCTS OF ACID AMIDE-LIKE CONSTITUTION AND PROCESS OF PREPARING THEM

Gerhard Balle and Heinz Schild, Frankfort-on-the-Main, Germany, assignors to I. G. Farbenindustrie Aktiengesellschaft, Frankfort-on-the-Main, Germany

No Drawing. Application June 13, 1938, Serial No. 213,424. In Germany June 22, 1937

6 Claims. (Cl. 260—519)

It is known that by the "Schotten-Baumann" reaction carboxylic acid amidelike condensation products may be made by causing the halides of natural fatty acids to react with amino-carboxylic acids or alkali salts thereof.

These amidelike condensation products and especially their water-soluble salts have obtained a commercial importance as wetting, dispersing and cleansing agents.

10 Now we have found that amidelike condensation products having valuable properties may be obtained on a 100% synthetical base, by causing an amino-carboxylic acid or a water-soluble salt thereof to react with an isocyclic, for instance, aromatic or hydroaromatic, carboxylic acid of the general formula:

(R)_n.A.X

wherein R stands for a hydrocarbon radical with at least 4 carbon atoms, n is the whole number 1 or a multiple of 1, A is an isocyclic ring system, X a COOH group or an aliphatic hydrocarbon radical carrying a COOH group the carbon chain of which may be interrupted by hetero-atoms and which is bound to A either directly or by way of a hetero-atom, for instance, O, S or N, the isocyclic carboxylic acid being suitably used in the form of a halide.

There may be obtained products of the following general formula:

35 wherein R₁ stands for a hydrocarbon radical of at least 4 carbon atoms, n stands for an integer, A stands for an isocyclic ring, X stands for a member of the group consisting of CO, Z.CO, O.Z.CO, S.Z.CO, NH.Z.CO, NR₄.Z.CO, Z being a member of the group consisting of aliphatic hydrocarbon radicals and aliphatic hydrocarbon radicals the carbon chain of which is interrupted by O, R₂ stands for a member of the group consisting of hydrogen and aliphatic hydrocarbon radicals, R₃ and R₄ stand for members of the group consisting of aliphatic and aromatic hydrocarbon radicals.

40 Among the carboxylic acids suitable for use in the invention there may be mentioned the following: aromatic or hydroaromatic carboxylic acids of the type of benzene- or hexahydrobenzene-carboxylic acids substituted by at least one hydrocarbon radical with at least 4 carbon atoms, such as isobutyl-benzoic acid, di-isobutylbenzoic acid, hexyl-benzoic acid, iso-octyl-toluic

acid, dodecyl-xylic acid, isotetradecyl-naphthoic acid, octodecyl-hexahydrobenzoic acid, iso-octyl-salicylic acid, furthermore carboxylic acids substituted in the ring system at least once in an analogous manner of the type of the 5 phenoxy- or hexahydrophenoxy-alkyl-carboxylic acids, such as iso-butyl-phenoxyacetic acid, isohexyl-cresoxyacetic acids, iso-octylxylene-hydroxypropionic acids, dibutylnaphthoxy-acetic acids, isododecyl-hexahydrophenoxyacetic acid, 10 isotetradecyl-phenoxy-alpha-butyric acid, para-cyclohexyl-phenoxy-alpha-lauric acid, ortho- and para-benzylphenoxy-propionic acid, para-phenyl-phenoxyacetic acid, the hydrogenation products of these acids, iso-octyl-phenoxyethoxyacetic acid, dodecylphenyl-pentaglycol ether acetic acid, iso-octyl-phenylglycine, iso-heptylphenyl-mercapto-acetic acid, furthermore carboxylic acids of the type of the substituted phenylacetic acid, such as the tri-butyl-phenyl-acetic acid, iso-octylphenyl-hydrocinnamic acid, butylphenyl-butyric acid, dodecyl-benzoyl-propionic acid, cyclohexyl-benzoyl-benzoic acid.

20 Amino-carboxylic acids which may be caused to react with the above-mentioned aromatic or hydroaromatic carboxylic acids are, for instance: amino-acetic acid, imino-diacetic acid, methyl-amino-acetic acid, amino-propionic acid, amino-butyric acid, alpha-methylamino-lauric acid; amino-acid mixtures, such as are present in the 25 different stages of decomposition of natural albuminous compounds such as wool, silk, horn, leather; amino-benzoic acid, amino-phenoxy-acetic acid, amino-salicylic acid.

30 The reaction between members of the two classes of bodies to form the amidelike condensation product is preferably performed by causing a halide of the isocyclic carboxylic acid to act upon an aqueous solution of a salt of the amino-carboxylic acid. The reaction temperatures are generally situated between room 35 temperature and about 100° C., in most cases there is used a moderately elevated temperature, about 30° C. to 60° C. As agents for binding 40 the hydrogen halide there may be used, in this method of working, compounds having an alkaline action, or also organic bases.

45 The new products are obtained in the form of water-soluble salts, and some of them are 50 in the salt form crystalline, some of them are solid, crusty and pulverisable, others amorphous, viscous masses which in most cases still contain inorganic and organic salts. The free amide-carboxylic acids which are, in most cases, 55

easily obtainable by acidifying the solutions of their salts, are in part, crystalline, in part resinous to oily, more or less viscous masses, and generally colorless to feebly brown; they are in part soluble and in part insoluble in water.

The solutions of the alkali or ammonium salts of the amide-carboxylic acids, also their salts with organic bases, yield, on shaking, a strong, soap-like foam and are good wetting, dispersing, emulsifying and purifying agents, their effect being in general considerably better than that of soaps or of soap substitutes obtained from natural fats.

As the new amide-carboxylic acids and their salts are soluble in many organic solvents, they may be used in combination with such solvents. According to the intended purpose, they may be used as such or mixed with each other. They may also be combined, in order to obtain special effects, with fatty acids, with carboxylic acids formed by oxidizing paraffin, or with the water-soluble salts of such acids, with soap substitutes or other textile adjuvants, with sodium carbonate, sodium pyrophosphate and other phosphates, with other products having a similar action on the salts causing the hardness of water or also with bleaching agents.

The following examples serve to illustrate the invention, but they are not intended to limit it thereto; the parts are by weight:

1. 121 parts of the sodium salt of sarcosine in an aqueous solution of 20 per cent. strength are heated to 40° C. to 50° C., 366 parts of tetradecyl-phenoxyacetic acid chloride are run into this solution while it is kept permanently alkaline by adding caustic soda solution of 35 per cent. strength. The reaction is performed in a kneading apparatus, in order to mix intimately the two components entering into reaction. After having kneaded the mass well for 4 hours, the alkalinity of the mass being continuously controlled, the product is made neutral by addition of dilute sulfuric acid. It forms, after drying and pulverizing, a light-yellow dust which dissolves, when stirred with water, and yields a strongly foaming solution having a good washing effect.

2. 265 parts of iso-octyl-toluic acid chloride are introduced, at 30° C. to 40° C., into a solution of 14 per cent. strength of 106 parts of sodium amino-acetate. By addition of caustic soda solution of 35 per cent. strength, the solution is kept alkaline. After a 4 hours' stirring, at the same temperature, the mass is made neutral by adding dilute sulfuric acid. The product which is obtained in the form of a yellowish-white paste has a good wetting power.

3. 332 parts of octylnaphthoxyacetic acid chloride dissolved in 400 parts of carbon tetrachloride are added drop by drop at 50° C. to 60° C., into an aqueous solution of 13 per cent. strength of 121 parts of the sodium salt of sarcosine.

The solution is kept alkaline by adding caustic soda solution of 35 per cent. strength. After having stirred the mass, for 5 hours, at the indicated temperature, the product is obtained, after expelling of the carbon tetrachloride, in the form of a yellowish paste, which is soluble in water and has a good foaming power.

4. At 20° C. to 30° C., 337 parts of dodecyl-phenoxyacetic acid chloride are introduced, in a kneading apparatus, into an aqueous solution of 15 per cent. strength of 194 parts of sodium imino-diacetate. The reaction of the mass is kept permanently alkaline by addition of caustic soda solution of 35 per cent. strength.

After a further stirring, for 4 hours, at the above-indicated temperature, part of the excess of the water of the yellow paste may be eliminated by drying under reduced pressure.

5. 338 parts of dodecyl-phenoxyacetic acid chloride dissolved in 300 parts of carbon tetrachloride are introduced into an aqueous solution of 20 per cent. strength of 176 parts of sodium para-aminobenzoate, and the temperature is maintained at 40° C. to 50° C. After a further stirring for 4 hours the carbon tetrachloride is evaporated and the mass is dried. A sodium salt soluble in water and having a good foaming power is obtained.

6. 231 parts of octyl-phenoxyethoxyacetic acid chloride are introduced, at 40° C. to 50° C., into a solution of 20 per cent. strength of 121 parts of the sodium salt of sarcosine and the solution is permanently kept alkaline by addition of an industrial mixture of mono-, di- and triethanolamine. The aqueous yellow paste is a good wetting agent.

7. 353 parts of dodecyl-phenylthio-glycolic acid chloride are introduced, at 30° C. to 40° C., into a solution of 30 per cent. strength of 106 parts of sodium aminoacetate and the solution is kept alkaline. The yellow paste which is soluble in water may be used as wetting agent.

8. 337 parts of dodecyl-phenylaminoacetic acid chloride are introduced, at 50° C. to 60° C., into a commercial mixture of 40 per cent. strength of peptides being obtained by treating for 6 hours finely pulverized leather waste at 130° C. in an autoclave and subsequently treating it with caustic soda solution. The solution is kept alkaline by adding caustic soda solution drop by drop. The aqueous paste is suitable as washing agent and yields a good foam.

We claim:

1. As new compounds the products of the general formula:

45

wherein R_1 stands for a hydrocarbon radical of at least 4 carbon atoms, n stands for an integer, A stands for an isocyclic ring, X stands for a member of the group consisting of CO, Z.CO, O.Z.CO, S.Z.CO, NH.Z.CO, NR₄.Z.CO, Z being a member of the group consisting of aliphatic hydrocarbon radicals and aliphatic hydrocarbon radicals the carbon chain of which is interrupted by O, R_2 stands for a member of the group consisting of hydrogen and aliphatic hydrocarbon radicals, R_3 and R_4 stands for members of the group consisting of aliphatic and aromatic hydrocarbon radicals.

2. As new compounds the products of the general formula:

60

wherein R_1 stands for a hydrocarbon radical of at least 4 carbon atoms, n stands for a whole number of the group consisting of 1 and 2, A stands for a six-membered isocyclic ring, X stands for a member of the group consisting of CO, Z.CO, O.Z.CO, S.Z.CO, NH.Z.CO, NR₄.Z.CO, Z being a member of the group consisting of aliphatic hydrocarbon radicals and aliphatic hydrocarbon radicals the carbon chain of which is interrupted by O, R_2 stands for a member of the group consisting of hydrogen and aliphatic hydrocarbon radicals.

hydrocarbon radicals, R₃ and R₄ stand for members of the group consisting of aliphatic and aromatic hydrocarbon radicals.

3. As new compounds the products of the general formula:

- 10 wherein R₁ stands for an aliphatic hydrocarbon radical of at least 4 carbon atoms, A stands for a member of the group consisting of the benzene ring and the cyclohexane ring, X stands for a member of the group consisting of CO, Z.CO, 15 O.Z.CO, S.Z.CO, NH.Z.CO, NR₄.Z.CO, Z being a member of the group consisting of aliphatic hydrocarbon radicals and aliphatic hydrocarbon radicals the carbon chain of which is interrupted by O, R₂ stands for a member of the group consisting of hydrogen and aliphatic hydrocarbon radicals, R₃ is an aliphatic hydrocarbon radical, R₄ stands for a member of the group consisting of aliphatic and aromatic hydrocarbon radicals.
- 20 4. As new compounds the products of the general formula:

- 30 wherein R₁ stands for an aliphatic hydrocarbon

radical having 12 carbon atoms, R₂ stands for a member of the group consisting of hydrogen and aliphatic hydrocarbon radicals, R₃ is an aliphatic hydrocarbon radical.

5. As new compounds the products of the general formula

wherein R₁ stands for an aliphatic hydrocarbon radical having 14 carbon atoms, R₂ stands for a member of the group consisting of hydrogen and aliphatic hydrocarbon radicals, R₃ is an aliphatic hydrocarbon radical.

6. As new compounds the products of the general formula:

wherein R₁ stands for an aliphatic hydrocarbon radical having 14 carbon atoms, R₂ stands for a member of the group consisting of hydrogen and aliphatic hydrocarbon radicals, R₃ is an aliphatic hydrocarbon radical.
